US00D840820S

(12) **United States Design Patent** (10) **Patent No.:** **US D840,820 S**
(45) **Date of Patent:** **** Feb. 19, 2019**

(54) **INSERT FOR COSMETIC CONTAINER**

(71) Applicant: **F.S. KOREA INDUSTRIES INC.**,
Seoul (KR)

(72) Inventor: **Jae Kwang Hwang**, Seoul (KR)

(73) Assignee: **F.S.KOREA INDUSTRIES INC.**,
Seoul (KR)

(**) Term: **15 Years**

(21) Appl. No.: **29/593,113**

(22) Filed: **Feb. 6, 2017**

(30) **Foreign Application Priority Data**

Aug. 10, 2016 (KR) 30-2016-0039088

(51) **LOC (11) Cl.** **09-07**

(52) **U.S. Cl.**
USPC **D9/456**

(57) **CLAIM**

The ornamental design for an insert for cosmetic container, as shown and described.

DESCRIPTION

FIG. 1 is a perspective view of an insert for cosmetic container showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom view thereof;

FIG. 8 is another perspective view thereof;

FIG. 9 is a cross sectional view of the insert for cosmetic container, taken in the direction of line 9-9 on FIG. 2; and, FIG. 10 is a perspective view thereof, showing the insert for cosmetic container in a position of use.

The broken lines are shown for the purpose of illustrating environmental subject matter and form no part of the claim.

1 Claim, 10 Drawing Sheets
